UNITED STATES PATENT OFFICE.

GASTON ERNEST SAMAIN, OF PARIS, FRANCE.

INTERNAL-COMBUSTION ENGINE.

1,261,058.

Specification of Letters Patent.

Patented Apr. 2, 1918.

Application filed November 9, 1916. Serial No. 130,386.

To all whom it may concern:

Be it known that I, GASTON ERNEST SAMAIN, of Paris, France, residing at Paris, Rue Lecourbe, in the Republic of France, have invented certain new and useful Improvements in Internal-Combustion Engines, and do hereby declare the following to be a full, clear, and exact description of the invention, such as will enable others skilled in the art to which it appertains to make and use the same.

The present invention relates to improvements in internal combustion engines, more particularly to those operating in the four-cycle system controlled by means of a single sleeve to which reciprocating movement is given from a shaft running at half engine speed.

In certain of these engines three or more ports have been provided to allow of entry of the charge, exhausting of the products of combustion and if desired of an auxiliary exhaust, and of the auxiliary inlet of air or mixture.

In the arrangement according to the present invention the cylinder containing the working piston is provided with a port at the upper part of the cylinder for the entry of explosive mixture, another in the upper part of the cylinder for the scavenging of the burnt gas and for the filling of the cylinder, while in the lower part of the cylinder a port for an exhaust outlet is provided. Communication with the interior of the cylinder is established through ports in the sleeve.

The controlling parts are arranged in such a manner that the piston at the end of its stroke co-operates with the sleeve to uncover the large exhaust opening for the escape of the products of combustion. As the piston rises the remainder of the burnt gas is expelled through the scavenging port above mentioned while this scavenging port also serves for charging the cylinder after the closing of the ordinary fresh mixture admission port to insure constant compression under all conditions.

The invention is more particularly described with reference to the accompanying drawings in which:

Figure 1 is a sectional view through the axle of an internal combustion engine provided with the improvements of the invention.

Figs. 2, 3, 4, and 5 are diagrammatic

drawings showing the relative positions of the sleeve and of the piston during the strokes of this latter.

The cylinder C is provided on its base with a large exhaust port M and at the top with a port H serving for the inlet of the charge. At the top is also provided a port K for scavenging and for assisting in the charging of the cylinder. The sleeve F is provided on its base with a port m and at the top with a port h.

The sleeve F is operated by a connecting rod b and crank from a shaft A running at half-engine speed. The main shaft is turned from the working piston P through the usual connecting rod B. The path of the sleeve is such that at predeterminate moments the port m and h coincide with the ports M, K, H in the cylinder serving for the exhausting of the cylinder, the scavenging of the same and the entry of a fresh charge to the same.

In Fig. 1, the piston is shown at the half of its suction stroke, the inlet port H is wide open by the port h of the sleeve which has a downward and upward motion during the downward motion of the piston. During about the $\frac{1}{10}$ of the suction stroke the port H is progressively opened and closed by h of the sleeve.

In Fig. 2, the piston has about ended its suction stroke and the inlet port H is completely closed. On the other hand, the scavenging port K is about to open by h of the sleeve for a very short time to complete the filling of the cylinder with fresh air or even with burnt gas if the pressure of the cylinder is lower than atmospheric pressure, consequently rendering the compression constant. During this stroke, the exhaust port M is completely closed.

In the Fig. 3, the piston is beginning its compression stroke and during its stroke the ports M, K, H are completely closed.

In the Fig. 4, the piston has ended its compression stroke and is beginning its working stroke. The explosion has taken place by means of an ignition plug screwed in at e or the like. During the downward motion of the piston the ports H and K remain completely sealed. When the piston is about to arrive at the bottom of the working stroke, the exhaust port M is about to open to give a large exhaust area for the escape of products of combustion. The exhaust through the port M commences slightly

before the piston arrives at the bottom of its stroke, which exhaust port is wide open when the piston rises as shown in Fig. 5. During this stroke the sleeve has a downward motion and the remainder of the burnt charge is expelled through the ports *h* and *K*.

It will be seen that the port *K* in the cylinder is arranged higher than the inlet port *H*. This arrangement is very important because it prevents the products of combustion being pushed back into the carburetor. The port *K* serves not only as an extra scavenging port for the gas but also allows for the feeding of the cylinders with further air. If the pressure in this cylinder is equal to atmospheric pressure, no air or burnt gas will enter through the port *K* on the inlet stroke, but if the pressure in the cylinder is at the end of the inlet stroke less than atmospheric pressure, air will enter which will insure constant compression under all conditions. Further, this arrangement allows the use of heavy fuels as the normal inlet port can be used for the introduction of the fuel carbureted with a very small amount of air where it is better, volatilized in the cylinder and at the end of the inlet stroke only will the necessary quantity of air be added to the charge.

The construction is very simple and does not require the sleeve packing/rings and con-

sequently it can be made quite thin whereby the added advantage of enhanced cooling is obtained. This is particularly due to the shrouding of the sleeve in the head of the cylinder as shown.

Having now particularly described and ascertained the nature of my said invention and in what manner the same is to be performed, I declare that what I claim is:

1. In a four cycle internal combustion engine, a cylinder having an exhaust port near its outer end, and inlet and scavenging ports near its inner end, a piston, a sleeve between the piston and cylinder having an opening adapted to register with the exhaust port, and having a second opening adapted to register successively with the inlet and scavenging ports, a controlling shaft for the sleeve geared to make one revolution for two of the main shaft, and a crank and connecting rod connection between said controlling shaft and the sleeve.

2. An engine of the character called for in claim 1, further characterized by the inlet port being placed near the scavenging port and between it and the exhaust port.

In testimony whereof, I have affixed my signature, in presence of two witnesses.

GASTON ERNEST SAMAIN.
